Plate 2

Thomas A. Herricks design for stove plate

Assigned to

Lucius M. Leonard, Taunton, Mass.

Fig. 2

Des. 457

Thomas A. Herrick of Boston Mass.
Assignor to Samuel M. Leonard of Taunton Mass.
Letters Patent No 4457. Dated May 19th 1852

The schedule referred to in these Letters Patent and making part of the same.

To all Persons to whom these Presents shall come.

Be it known that

Thomas A. Herrick of Boston in the County of Suffolk and State of Massa-

Chusells have produced a new and original design for the side plate of a cooking stove, and I do hereby declare that the said new design is fully described and represented in the following specification and accompanying drawings to which reference is hereinafter made.

The figures of the accompanying plates of drawings represent my new design. In Plate 1 fig 1 is an elevation of the side plate and in Plate 2 fig 2 is a section of the same taken in the plane of the line A B fig 1.

The edges of the plate have around them the mouldings a, a & c and the oven door has the mouldings A A & c and the short ribs b b with the small stars c c in each corner. In the centre of the door is the circular moulding d, d enclosing the convex ribs e e and the main panel of the door is ornamented with the ribs or rays f f and the raised rays g g. The fire chamber door and the panel ff is ornamented with the mouldings A A ribs b b with the stars c c and moulding d d enclosing the ribs e e. The panel g g over the oven door is ornamented with the ribs b b stars c c and spearheads h h enclosed by the moulding i i.

Having thus described my new design I shall state my claim as follows.

What I claim as my production and desire to have secured to me by Letters Patent is the new design consisting of the ornamental mouldings, ribs, and rays herein above described and represented in the drawings for the side plate of a cooking stove.
